WINDING MACHINE FOR BRASS BOBBINS

Reginald Samuel Needham, Littleover, England

Application November 19, 1952, Serial No. 321,379

6 Claims. (Cl. 242—35.5)

This invention relates to winding machines for brass bobbins such as are used in the making of plain net or lace. The term "brass bobbins" is a trade term for a type of bobbin commonly used in plain net and lace making machines. It does not mean that the bobbin is necessarily made of brass, although this is usually the case. The bobbins usually consist of two circular plates or discs each having the half of a central boss on its inner face, and they are secured together by riveting or otherwise so that there is a clearance or groove usually not more than about one-thirtieth of an inch wide between the two plates in which the desired length of thread is wound.

The usual type of winding machine for these bobbins requires that each bobbin shall be separately threaded by hand before winding begins, and that each thread shall be cut off by hand when the bobbin is full. In other words the type of machine in common use effects rotation of the bobbins to wind on the necessary length of thread, which is determined by means of a suitable automatic measuring device. It does not effect the change over from the full bobbins to fresh ones, nor does it cut off the threads.

The object of this invention is therefore to provide a fully automatic winding machine for brass bobbins in which the winding, change-over and thread-cutting will all be accomplished by the machine itself.

According to the present invention a carrier for a number of bobbin-spindles or sets of bobbins is operated in a succession of intermittent movements of limited extent, by control mechanism whose actuation is derived from the automatic measuring device, the movement of the carrier serving to take one spindle or set of bobbins out of the winding position and feed the threads onto the bobbins of a fresh spindle or set which is brought by the movement of the carrier into the winding position.

The movements of the carrier are preferably rotary movements, although it is possible that a forwardly travelling carrier could be devised.

The control mechanism is also preferably arranged to operate mechanism for cutting off the threads from the fully wound bobbins.

The action of the control mechanism preferably consists in operating a clutch mechanism to disconnect the drive from the bobbin spindle which has been wound, then to advance the carrier to take the wound bobbins out of the winding position, and to bring another spindle of empty bobbins into the winding position as the movement of the carrier is completed, and finally to re-engage the clutch mechanism and take up the drive to the fresh spindle of bobbins.

The actual means employed to initiate the intermittent movements of the control mechanism may vary according to what is most convenient. For instance if an electrical measuring device is used (and such devices are well known in themselves) it will be convenient to initiate the control mechanism by electrical means, for example the measuring device may be arranged at the conclusion of each winding operation to complete a solenoid circuit,

2

the movement of the solenoid plunger being arranged to disconnect the drive from the winding means and bring into operation the drive by which the carrier wheel is moved.

5 It is convenient to provide cam means on the carrier itself to start up the winding mechanism as each bobbin spindle comes into the driving position and to disconnect the drive to the carrier.

In the winding position the threads may be held in alignment with their respective bobbins by means of a suitable reed or guide member. The assembly may consist of a series of plates with narrow clearances between them, corresponding to the gauge of the bobbins. One reed can be readily interchanged for another to suit different gauges of bobbin. Any suitable standard thread guides may lead the threads into the clearances in the reed. As the winding operation is completed and the carrier moves on, the action of the reed in conjunction with the changing position of the bobbins feeds the threads into the next set of bobbins as it moves into the winding position.

It is at this stage that the cutting mechanism is actuated and this may comprise a cutter blade which is actuated to bear on the threads and sever them at a point between the fully wound bobbins off which they come and the empty bobbins into which they have been inserted. The aforesaid cutter blade may be cam-operated in synchrony with the movements of the carrier.

A constructional form of the invention will now be described with reference to the accompany drawings, in which:

Figure 1 is a side elevation.

Figure 2 is an end view, partly in section.

Figure 3 is an electrical circuit diagram.

Fig. 4 is a fragmental view, partly in cross-section of the re-set device for the electrical measuring unit.

The machine comprises a frame 10 in which an electric motor 11 is mounted. The motor 11 drives a reduction gearbox 12. The output spindle 13 of the gearbox 12 drives a pulley 14 connected by a belt 15 with a pulley 16 on a worm shaft 17 on which a worm 18 is fitted. The worm 18 drives a worm wheel 19 mounted on a countershaft 20.

The countershaft 20 drives a Geneva mechanism 21, 22 which imparts an intermittent rotary movement (in the example shown 45°) to a shaft 24 on which a bobbin-spindle carrier 25 is mounted. The carrier 25 is arranged to carry eight spindles 26 on which a series of brass bobbins 27 are fitted.

50 The spindles of bobbins are fed to the carrier down an inclined chute 30 and their loading into the carrier is controlled by a rotary star member 31 having peaks 32 extending along it. This member is operated by gear wheels 33, 34 operated by a sprocket 35, chain 36 and further sprockets 37 in synchrony with the rotary movements of the carrier. Each time the carrier advances the loading device 31 is rotated to deliver another bobbin-spindle into openings in the end bearings or housings 39 which support it in the carrier.

60 After having been loaded into the carrier each spindle of bobbins advances in a succession of part rotary movements in an anti-clockwise direction as viewed in Figure 1 until it is nearly in the top dead centre. At this point the bobbins receive threads which pass through reeds 40, 41 to align each thread with a bobbin. One form of reed consists of an assembly of plates with narrow clearances between them corresponding to the gauge of the bobbins but various types of reed device are known in the art for thread alignment and this invention is not confined to any particular type. The threads are indicated at 42. Thus threaded the bobbins arrive in the winding position at top dead centre. The winding operation is ef-

fected by rotating the bobbin spindle while in the top dead centre position by motor 45. This is effected by an electric motor 45 operating a magnetic clutch 46, 47. The control of this winding movement is derived from a conventional type of electric measuring device 48 which can be set to operate at any predetermined length of thread. This is wired through a solenoid type of switch 49 so that after the predetermined length of thread has been wound on to the bobbins the measuring device contacts 48^a close, and act to operate the solenoid switch 49 which breaks the circuit controlling the supply of current to the motor 45. The motor 45 thereupon stops and the magnetic clutch 46, 47 is de-energised, so that winding ceases. Simultaneously the solenoid switch 49 acts to close the circuit controlling the current supply to the motor 11, which thereupon operates the Geneva mechanism and the wound spindle of bobbins is carried forward out of the top dead centre position. The electrical measuring device has a pivotal trigger 51. When the carrier has made its predetermined amount of rotary movement one of a series of cams 52 on the carrier (there being one such cam for each bobbin-spindle) is arranged to trip a mechanical re-set device in the form of a pivoted lever 53 which is connected by a flexible cable with the trigger 51. The trigger is thereby operated, and acts to re-set the electrical measuring 48. When this is thus re-set it automatically re-opens the contacts 48^a, which is an ordinary micro-switch type device of standard pattern and is operated in the ordinary conventional way when the rotary element in the measuring device attains the actuating position. There is no connection between the trigger 51 and the contacts 48^a; the trigger merely acts to re-set the measuring device 48, and the measuring device itself re-opens the contacts 48^a as is customary in such measuring devices, thereby stopping the motor 11 and re-starting the motor 45, while at the same time re-setting the measuring device at zero.

As a wound spindle of bobbins is carried forward out of the top dead centre position a cam 55 on the counter-shaft 20 actuates a weighted rod 56 which is pivotally connected at 57 with a rocking lever 58 pivoted on the frame at 59 and connected to a cutting-off knife 60, so that each time a spindle of bobbins fully wound leaves the winding position the cam 55 operates the knife to cut off the threads after these have been threaded into the next spindle of bobbins.

Each spindle of wound bobbins after the threads have been cut off in this way arrives at the unloading position where an inclined chute 62 projects into the path of the bobbins and extends under them but is clear of the end bearings or housings in which the bobbin spindle rests. Therefore on the next succeeding movement of the carrier the chute 62 will retain the spindle of bobbins as the bearings or housings are moved onwards by the carrier in readiness for loading, while the spindle of wound bobbins rolls down the chute 62.

I claim:

1. A brass bobbin winding machine comprising a car-

rier mounted for rotary movement, drive means to rotate the carrier, a number of bobbin spindles removably supported by the carrier parallel to its axis of rotation, a number of bobbins supported side by side on each of the spindles, means feeding a corresponding number of threads one into each bobbin on one of the spindles, means acting thereafter to rotate such spindle about its own axis, means operatively connected intermediate the drive means and the carrier to impart intermittent movement to the carrier, means measuring the length of thread wound on to the bobbins effective to stop operation of the further means rotating the spindle after the requisite length of thread has been wound thereon, and means connecting the measuring means with the drive means to initiate the intermittent movement of the carrier when such spindle rotation is stopped.

2. A machine according to claim 1 in which the measuring device is arranged when the desired length of threads has been wound on to the bobbins to complete a solenoid circuit, said solenoid being associated with means by which the bobbin spindle has been rotated and drive means by which the carrier is moved, so that at the conclusion of each winding operation the drive to the bobbin spindle is disconnected and the drive to the carrier brought into operation.

3. A machine according to claim 2 having cam means on the carrier, said cam means being adapted to start up the drive to the bobbin spindle whose bobbins are about to be wound and to disconnect the drive to the carrier.

4. A machine according to claim 1 in which a cutting-off blade is provided, means being provided to actuate said cutting-off blade to bear on the threads and sever them where they come from the fully-wound bobbins.

5. A machine according to claim 4 in which the cutting blade is actuated in synchrony with the movement of the carrier.

6. A machine according to claim 1 in which the electrical measuring device is provided with a mechanical re-setting device which is tripped by a cam on the carrier, said re-setting device serving not only to re-set the measuring device at zero but also at the same time to re-start the drive to the bobbin spindle whose bobbins are about to be wound.
